ATTORNEY

UNITED STATES PATENT OFFICE

JOSEPH LEVY, OF BROOKLYN, NEW YORK, ASSIGNOR TO CENTURY LIGHTING EQUIPMENT, INC., OF NEW YORK, N. Y., A CORPORATION OF NEW YORK

SPOT AND FLOOD LIGHT PROJECTOR

Application filed June 26, 1930. Serial No. 463,852.

This invention relates to accessories for lighting apparatus, such as used to modify spot and flood lights for producing novel theatrical, advertisement, show window display and other lighting effects. More particularly, the invention is directed to an improved interlocking means for releasably retaining light modifying accessories, such as color frames, color boxes, color wheels and flickering effect mechanisms such as, the so-called lobsterscopes or optiscopes, on conventional spot and flood light projectors or lanterns.

Among the objects of the invention is to provide an improved interlocking means for releasably retaining a light modifying accessory on spot or flood light projectors comprising few and simple parts, which shall positively secure and retain the accessory to the light projecting apparatus in proper alignment, which shall permit easy and quick removal and replacement thereof, which shall be cheap to manufacture, and practical and efficient to a high degree in use.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawings, in which is shown one of the various possible illustrative embodiments of this invention.

Fig. 1 is a front elevational view of a conventional stand or hanging type of swingably mounted spot light projecting apparatus fitted with the color frame holder having an improved releasable retaining means embodying the invention.

Fig. 2 is a fragmentary side elevational view showing the front end of said light projecting apparatus and the color frame holder, a portion of the casings of said apparatus and holder being broken away to expose the interior construction.

Fig. 3 is a cross-sectional view taken through the improved color frame holder removed from the apparatus, corresponding to a cut taken on line 3—3 in Fig. 1, and

Fig. 4 is a fragmentary top plan view of said color frame holder showing the improved spring closure and the releasable retaining means embodying the invention.

Referring in detail to the drawing, 10 denotes a conventional spot or flood light projector or lantern having a front side 10a formed with an opening 10b wherethrough light is projected from a suitable source (not shown) housed within the lantern in the well-understood manner.

Said lantern 10 may be of the stand or hanging type and may be provided with a suitable swivel fitting 11 to permit swinging the lantern for projecting the light in all directions. Said lantern also has on its front side 10a suitable means in the form of grooved slides 12 for demountably supporting a light modifying accessory, such as a color frame, color box, color wheel or flicker effect mechanism, such as a lobsterscope or optiscope in the path of the light being projected from the lantern opening 10b. Said slides 12 each have projecting lugs 12a wherethrough screws 13 pass for securing said slides in spaced parallel alignment adjacent the lantern opening 10b.

Only one form of light modifying accessory embodying the invention is here disclosed and is seen to comprise a holder 14 adapted to have inserted therein color screens C of any conventional construction, said holder being provided with improved releasable fastening means for engaging and interlocking with the grooved slides 12 to retain said accessory against accidental movement from its set registered position with the lantern opening 10b in the manner hereinafter described.

The color frame holder 14 may comprise the casing of a rectangular cross-section having a rear wall 14a and a front wall 14b, each formed with openings 14c and 14d, respectively. Said openings are adapted to register with the lantern opening 10b to permit the passage of the projected light

therethrough, the modification of the projected light being accomplished by the color frame C which is interposed between said casing walls 14a and 14b, as shown in Figs. 1 and 2. One of the end walls 16 between walls 14a and 14b may be hinged, at 15, to the edge of the wall 14a to provide a removable closure or cover for the holder casing 14, the color frame C being inserted therein when said cover 16 is swung open. To retain the cover 16 shut for confining the color frame in holder 14, said cover may have a portion 16a thereof bent to extend along the front wall 14b. A ledge 16b upstands from said portion 16a for engaging with a flat spring 17 secured at one end to the wall 14b by rivets 18, the other end of said spring forming a resilient latch engaging with the cover ledge 16b.

Secured to the casing wall 14b, for aligning the holder 14 between the grooved slides 12 with the lantern opening 10b there is provided the suitable fastening means in the form of flat springs 19 having one end 19a of each permanently secured to said wall 14b by rivets 20. The other end 19b of each spring 19 forms a resilient structure extending outwardly from the wall 14b and carries a stop member 21 from which a locking flange 21a extends. Said stop members 21 interlock with the opposite ends 12b of the slides 12, the flanges 21a engaging over the edge of the slide ends 12b, as shown in Figs. 1 and 2.

The practical application of the invention will now be apparent. Any light modifying accessory, such as for example, the holder 14, is provided with the improved releasable spring fastening means for retaining said accessory in proper position between the grooved slides 12. Thus when the holder 14 is mounted in position with the stop members 21 engaged with the ends of said slides 12, the holder will be in proper alignment to allow projected light to pass through the openings 14c and 14d. The holder 14 then cannot be accidentally displaced from its aligned position no matter how much the lantern 10 is moved or swung about. The color frame C may be readily removed or replaced by simply releasing the cover 16 from its engagement with the spring 17 to permit swinging the latter open for giving access to the interior of the casing, as is readily understood. To remove the holder 14 from its mounted position on the lantern, the stop members at one end of the slides are simply depressed to allow shifting the holder along the grooved slides.

Any other light modifying accessories may also be provided with improved means as described above for fastening the holder 14 to the lantern 10. Accessories so constructed may be mounted on or dismounted

from the lantern 10 in the same manner as described above for the holder 14.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. In a light modifying accessory adapted to be removably supported between a pair of grooved slides of a conventional light projecting apparatus, flat spring means secured to the accessory, and spaced projecting members carried on said means for engaging with one of said slides.

2. A light modifying accessory adapted to be removably supported between a pair of grooved slides of a conventional light projecting apparatus, said accessory having an opening adapted to align with the side of said apparatus through which the light projects, and releasable spring means engaging the opposite end of one of said slides for retaining said accessory against movement from an aligned position with respect to the apparatus.

3. In a light modifying accessory adapted to be mounted between a pair of grooved slides of a light projection apparatus, a holder comprising a casing having parallel spaced walls formed with openings adapted to permit the passage of light therethrough, said casing adapted to contain a light modifying element therein between said spaced walls whereby light from the projection apparatus can pass through said light modifying element, and means for releasably locking said casing in the slides of the projection apparatus comprising a spring pressed member secured to said casing and engageable with a slide of the light projection apparatus.

In testimony whereof I affix my signature.
JOSEPH LEVY.
